US00D888887S

(12) **United States Design Patent** (10) **Patent No.:** **US D888,887 S**
Widom et al. (45) **Date of Patent:** **** Jun. 30, 2020**

(54) **AQUEOUS CONTAMINANT REMOVAL DEVICE**

(71) Applicant: **Pool Buddy, LLC**, Bedminster, NJ (US)

(72) Inventors: **David R. Widom**, Winchester, MA (US); **Timothy Jebara**, Far Hills, NJ (US); **Nour Jebara**, New York, NY (US)

(73) Assignee: **Pool Buddy LLC**, Bedminster, NJ (US)

(**) Term: **15 Years**

(21) Appl. No.: **29/725,328**

(22) Filed: **Feb. 24, 2020**

(51) LOC (12) Cl. **23-01**

(52) U.S. Cl.

USPC **D23/209**

(57) **CLAIM**

The ornamental design for an aqueous contaminant removal device, as shown and described.

DESCRIPTION

FIG. 1 is a top, front, right side perspective view; FIG. 2 is a front elevation view thereof, shown at an enlarged scale;

FIG. 3 is a rear elevation view thereof, shown at an enlarged scale;

FIG. 4 is a left side elevation view thereof;

FIG. 5 is a right side elevation view thereof;

FIG. 6 is a top plan view thereof; and

FIG. 7 is a bottom plan view thereof; and,

FIG. 8 is a Top, front, right side perspective view of an alternate embodiment thereof.

In the drawings, the broken lines are for the purpose of illustrating environment only, and form no part of the claimed design.

1 Claim, 6 Drawing Sheets
